SUPPORTING LEG ASSEMBLY FOR MARINE PLATFORM

George E. Suderow, New York, N.Y., assignor to De Long Corporation, New York, N.Y., a corporation of Delaware

Application September 28, 1956, Serial No. 612,809

7 Claims. (Cl. 61—46.5)

This invention relates to convertible marine platforms and more particularly to supporting leg assemblies for such platforms having jacking mechanisms for relatively manipulating the supporting leg assemblies and platform so that the latter can be converted from a floating platform to an elevated platform supported by the marine bottom above the water level and vice versa.

The present invention is particularly useful in the marine installation system such as disclosed in the Pointer application Serial No. 283,567 filed August 22, 1952, and issued on January 1, 1957, as Patent No. 2,775,869. In general, this system embodies the utilization of a floating platform which may be transported to any suitable marine site, as by tugs or the like, and which is provided with a series of elongated supporting legs which are utilized when the floating barge has been transported to the marine site to support the floating barge from the marine bottom in an elevated position above the water level. The system disclosed in the aforesaid Pointer application illustrates the use of tubular one-piece supporting legs which are initially moved through the platform guide means by means of pneumatically-operated jacking mechanisms until the lower end thereof are embedded in the marine bottom. Subsequently, the jacking mechanisms are operable to raise the platform on the supporting legs to a suitable height above the water level. With the platform thus supported, the same may be utilized for a variety of purposes. For example, permanent docks and piers have been constructed utilizing this system and it is also valuable in off-shore drilling operations where the platform is to be used temporarily. In the latter case, after operations have been completed, the jacking mechanisms are operable to permit the platform to be lowered on the supporting legs until the same is again floating on the surface of the water and then to subsequently raise the supporting legs clear of the marine bottom and to a transporting position on the platform.

In most installations it is of importance to provide an elevated platform which has a substantially unobstructed upper deck surface. Due to the uncertainty and the unevenness of the marine bottom, it is usually the case when dealing with one-piece supporting legs that the upper ends thereof will project above the upper deck surface of the platform when the latter has reached its operative elevated position. In permanent installations the supporting legs can be welded or otherwise permanently secured to the platform and the upper ends cut off, but this is not practical in temporary installations. Moreover, this procedure is time consuming and costly.

Consequently, in a later application, Serial No. 584,962, filed May 15, 1956, by George E. Suderow which is a continuation of application Serial No. 502,313, filed April 19, 1955, now abandoned, it was proposed to construct the supporting legs of telescopic sections so as to insure that there would be no obstructing upper supporting leg ends extending above the platform when the same is elevated to its operative position. Moreover, this sec-

2

tional construction renders the legs easier to handle and affords more flexibility in operation.

Briefly, the telescopic supporting leg assembly disclosed in the above-mentioned Suderow application includes a plurality of telescoping sections having jacking mechanisms between adjacent sections with the outer section mounted for vertical movement with respect to the platform by a jacking mechanism carried by the platform. The jacking mechanisms disclosed are of the pin type embodying horizontally slidable pins engageable in a series of longitudinally spaced apertures formed in the supporting leg sections. While this type of jacking mechanism provides a positive mechanical restraint against movement of the sections, the numerous manipulations required in the normal operation thereof, renders the same somewhat time consuming.

Accordingly, it is an object of the present invention to provide a telescopic supporting leg assembly having improved means for selectively effecting or restraining relative longitudinal movement between the sections thereof which is continuous in operation and, hence, fast in operation.

A still further object of the present invention is the provision of a supporting leg assembly of the type described which is simple in construction, easy to operate and economical to manufacture and maintain.

These and other objects will become more apparent during the course of the following detailed description and appended claims.

30 The invention may best be understood with reference to the accompanying drawings wherein an illustrative embodiment is shown.

In the drawings:

35 Figure 1 is a vertical sectional view of a supporting leg assembly embodying the principles of the present invention illustrating the same in its transporting position on a platform;

Figure 2 is a view similar to Figure 1 illustrating the manner in which the assembly is initially lowered with respect to the platform;

Figure 3 is a view similar to Figure 1 illustrating the manner in which the inner section of the assembly is initially moved downwardly;

Figure 4 is a view similar to Figure 3 illustrating the manner in which the inner section is locked in its downward position;

Figure 5 is a view similar to Figure 1 illustrating the upper portion of the assembly with an intermediate section moved downwardly;

Figure 5a is a view similar to Figure 5 showing the lower portion of the assembly;

Figure 6 is a view similar to Figure 1 illustrating the operative position of the upper portion of the assembly; and

Figure 6a is a view similar to Figure 6 illustrating the lower portion of the assembly.

Referring now more particularly to the drawings, there is shown a telescopic supporting leg assembly, generally indicated at 10, which embodies the principles of the present invention. As was briefly noted above, the assembly of the present invention is particularly adapted to be utilized in the marine construction system disclosed in the aforesaid Pointer application, although it will be understood that the same may be readily used for other purposes. As shown, the assembly 10 is mounted on a floating barge or platform, indicated at 12. It will be understood that in accordance with the Pointer system, the floating barge or platform 12 may be provided with a series of telescopic supporting leg assemblies 10 which may be cooperatively operated so as to effect the various

70

movements essential to the marine construction. In the drawings, only a portion of the floating platform is illustrated showing a single guide means 14 in the form of a vertical opening arranged to receive the single assembly 10.

The assembly 10 comprises a plurality of telescopically arranged tubular sections of any desired number. As shown, the assembly includes an outer section 16, a first intermediate section 18, a second intermediate section 20 and an inner section 22. The outer section 16 is mounted within an opening 14 of the platform 12 for substantially vertical movement therethrough. A jacking mechanism 24 is mounted on the platform 12 adjacent the opening 14 for effecting vertical movement of the outer section in either direction with respect to the platform. The jacking mechanism 24 preferably is constructed in the manner indicated in copending application Serial No. 523,323, filed July 10, 1955, by George E. Suderow, although it will be understood that other types of jacking mechanisms may be employed, if desired. Briefly, the jacking mechanism 24 includes an upper pair of opposed pins or bolts 26 mounted for horizontal reciprocating movement, as by a fluid pressure-operated ram unit 28, into and out of engagement with a series of openings 30 formed in the tubular wall of the outer section 16 in diametrically opposed relation. The jacking mechanism also includes a pair of opposed lower pins or bolts 32 mounted for horizontal reciprocation, as by fluid pressure-operated ram units 34. The pins 32 are also arranged to move into and out of apertures 30 formed in the outer section. Extending between the pins 26 and 32 and associated ram units 28 and 34 is a pair of vertically disposed ram units 36. By selectively engaging one pair of pins 26 or 32 and actuating the ram units 36, the outer section 16 may be moved vertically in either direction with respect to the platform 12 as is described in detail in the aforementioned Suderow application Serial No. 523,323.

In order to effect vertical movement of each section of the assembly 10 between fully extended and fully retracted positions, there is provided a pilot piston and cylinder unit, generally indicated at 38. The upper end of the outer section 16 is provided with a plate-like head 40 which may be rigidly secured thereto as by welding or the like. Extending downwardly from the central portion of the plate 40 is an elongated piston 42 having its lower end disposed adjacent the lower end of the outer section and provided with a piston 44. A cylinder 46 of substantially the same length as the piston rod 42 slidably receives the piston 44. The piston 44 is preferably provided with an O-ring 48 which engages the interior surface of the cylinder 46 so as to form a pressure-tight seal therewith. The upper end of the cylinder 46 includes an apertured disc-like closure member 50 having an O-ring 52 mounted in the interior surface thereof for engagement with the exterior surface of the piston rod 42. The lower end of the cylinder 46 is closed, as by a head member 53. The piston rod 42 may be of any suitable construction; however, as shown, it is tubular in form so as to receive fluid pressure lines 54 and 56, each of which extends through the central portion of the head plate 40, and downwardly into the hollow piston rod 42. The end of the line 54 extends to a port 58 formed in the wall of the piston rod above the piston 44 so as to communicate with the upper end of the cylinder, while the end of the line 56 leads to a port 60 extending through the piston 44 and communicating with the lower end of the cylinder. It will be seen that by introducing a pressurized fluid into line 56 and permitting the line 54 to exhaust, the cylinder 46 will be moved downwardly with respect to the piston 42 and, hence, the outer section 16. Reversal of the lines 54 and 56 from exhaust to pressurized fluid introduction and vice versa will cause the cylinder to move upwardly with respect to the outer section.

The first intermediate section 18 includes a pair of opposed locking units 62 which are selectively operable either to lock the first intermediate section with the outer section or to lock the first intermediate section to the pilot cylinder 46, so that the same can be moved vertically in either direction thereby with respect to the outer section. To this end, each unit 62 comprises a housing 64 having an outwardly extending pin or bolt 66 slidably mounted therein for horizontal reciprocation and an inwardly extending pin or bolt 68 mounted therein for horizontal reciprocation. Each pin is moved by means of a cylinder 70 having a spring-pressed plunger therein (not shown) which is connected to the associated pin and actuated by fluid under pressure from a line 15 72 extending from the cylinder 70 upwardly through a suitable aperture formed in the head plate 40 of the outer section 16. Preferably, the outer section is provided with upper and lower apertured bosses 74 and 76 for receiving the outer pins 66 so that the first intermediate section can be locked with respect thereto either in a fully retracted or fully extended position. In addition, the outer pins 66 may also be engaged within the apertures 30 formed in the tubular wall of the outer section as will hereinafter be more fully described. The inner pins 68 are arranged to enter apertures 78 formed in the upper wall of the cylinder 46 and in the disc-like head 50.

In a similar manner, the second intermediate section 20 may be alternately locked with the first intermediate section 18 or with the pilot cylinder 46. To this end, locking units 80, similar to the units 62, are mounted in diametrically opposed relation on the upper end of the second intermediate section. As before, each unit may include a housing 82 having an outer pin 84 and an inner pin 86 mounted therein for horizontal reciprocation. A cylinder unit 88 for each pin is mounted on the housing 82 for controlling the operation of the pin through a fluid pressure line 90 extending from the cylinder upwardly through a suitable aperture in the head plate 40 in the outer section 16. The first intermediate section is provided with upper and lower apertured bosses 92 and 94 for receiving the outer pins 84 so that the second intermediate section can be locked to the first intermediate section in either a fully extended or retracted position. The pilot cylinder 46 is provided with apertured bosses 96 for receiving the inner pins 86.

The inner section also includes a pair of opposed locking units 98 which may be similar to the units 62, and 80. Again, each unit may include a housing 100 having an outer pin 102 and an inner pin 104 mounted therein for horizontal reciprocation. A cylinder unit 106 for each pin is mounted on the housing 100 for controlling the operation of the pin through a fluid pressure line 108 which extends from the platform to the cylinder 50 through a suitable aperture formed in the head plate 40. The second intermediate section is provided with upper and lower apertured bosses 110 and 112 for receiving the outer pins 102 so as to lock the inner section with respect to the second intermediate section whether in retracted or fully extended positions. The pilot cylinder includes apertured bosses 114 for receiving the inner pins 104.

It will be understood that there is a suitable means on the platform for providing a source of fluid under pressure and controlling the introduction and exhaust of the same through the lines 54, 56, 72, 90, and 108. Such means is not shown in the drawings, but may be of conventional form, such as an air compressor feeding compressed air to the lines through suitable control valves. Preferably, the lines extending through the head plate of the outer section are connected to reels (not shown) mounted on the platform which are operable to pay out or retract the lines as desired during expansion or retraction of the sections.

The outer section 16 in addition to the head plate 40

may also be provided with an upper radially extending peripheral flange 116 which is arranged to engage the upper deck surface of the platform when the assembly is in its operative position. The remaining sections may be provided with reinforcing rings 118, 120 and 122 rigidly mounted on the exterior surface of their lower ends.

In utilizing the present invention in the system of the aforesaid Suderow application Serial No. 523,323, a series of telescopic supporting leg assemblies will be carried on the platform and simultaneously moved, as described in that application. With the above in mind, operation of a single assembly of the present invention will now be described. It will be noted that the arrangement of the locking units 62, 80 and 98 are such that independent relative vertical movement between any two adjacent sections of the assembly can be readily effected. Moreover, independent relative vertical movement in either direction between the outer section and the platform can be readily achieved by the jacking mechanism 24. Therefore, it will be understood that the precise manner or order in which the sections of the assembly are moved may be varied, as desired. However, a preferred order of actuation is disclosed in the drawings in which Figure 1 illustrates the assembly in its transporting position on the platform. In this position the pins 26 and 32 of the jacking mechanism 24 are extended into registering openings 30 in the outer section 16 and the pins of the units 62, 80 and 98 are extended so as to engage the adjacent section and the pilot cylinder 46. In this manner all of the sections of the assembly as well as the assembly itself are retained in their transporting position by a mechanical locking action. In this position the platform is floated, as by tugs or the like, to a suitable marine site where operations are to be carried on.

When the platform has reached the site of operation, jacking mechanism 24 is actuated in the manner described in the above-mentioned Suderow application Serial No. 523,323 so as to lower the entire assembly in its locked condition until the upper end of the outer section is disposed above the estimated bottom of the marine site a distance equal to that in which the platform will ultimately operate above the water level taking into account the draft of the platform, as shown in Figure 2. It will be noted that the condition of the various locking units of the assembly are in the same position as illustrated in Figure 1. Next, the inner pins 68 and 86 of the units 62 and 80 are moved out of engagement with the associated pilot cylinder apertures and the outer pins 102 of the units 98 are moved out of engagement with the apertured bosses 110 of the second intermediate section. The inner section is now locked to the pilot cylinder and free of engagement with the second intermediate section so that it will move with the pilot cylinder. The source of pressurized fluid is then introduced into the lower portion of the pilot cylinder through the line 56 and port 60 while permitting the fluid to exhaust through the port 58 and line 54. In this manner, the inner section is moved downwardly with the pilot cylinder 46 until it reaches its fully extended position, as shown in Figure 3. Next, the outer pins 102 are actuated to move into engagement with the lower apertured bosses 112 of the second intermediate section 20. The inner pins 104 are then released from their position of engagement within the apertured bosses 114 of the pilot cylinder permitting the latter to again be moved upwardly, in the position illustrated in Figure 4, by reversing the flow through the ports 58 and 60.

Next, the inner pins 86 of the units 80 mounted on the upper end of the intermediate section 20 are actuated to move into the apertures of the bosses 96 carried by the pilot cylinder and the outer pins 84 moved out

of engagement with the upper apertures of the bosses 92 of the first intermediate section. The pilot cylinder is now actuated to move the second intermediate section and, hence, also the inner section, downwardly until the same reaches its fully extended position, as shown in Figures 5 and 5a, at which time the outer pins 84 are engaged within the lower apertured bosses 94 of the section 18 and the inner pins 86 are removed out of the apertured bosses 96 of the pilot cylinder. The pilot cylinder is again moved upwardly into its upper limiting position so that the inner pins 68 of the unit 62 mounted on the upper end of the first intermediate section can be moved inwardly into engagement with the opening 78 formed in the upper end thereof. The outer pins 66 are withdrawn from the apertured bosses 74 and the pilot cylinder is again moved downwardly until the first intermediate section reaches its fully extended position, as shown in Figures 6 and 6a.

In this regard, it will be noted that during the downward movement of either of the intermediate sections, the lower end of the inner section may engage the marine bottom depending upon the depth thereof. The operation of the pilot cylinder is such as to drive the lower end of the inner section into firm engagement with the marine bottom during its downward movement with the associated intermediate section. It will also be noted that the first intermediate section may be locked by actuation of the outer pins 66 in several vertical positions of adjustment intermediate its fully retracted and fully extended positions by engagement within the apertures 30 formed in the tubular wall thereof. In like manner, to provide a wider range of adjustability so as to accommodate marine bottoms which are relatively shallow, the first intermediate section may be provided with a series of longitudinally spaced apertures 124 for selectively receiving the outer pins 84 carried by the second intermediate section.

After the sections of the assembly have been extended a desired amount sufficient to embed the lower end of the inner section in the marine bottom, the jacking mechanism 24 is actuated to raise the platform 12 on the outer section 16 of the assembly until the same reaches a position adjacent the upper end of the outer section with the upper deck surface of the platform in substantially flush relationship with respect to the upper end of the outer section and the entire assembly is pinned off.

Where temporary operations have been completed, or for some other reason, it is desired to move the platform to a different marine site, the above procedure may be reversed so as to move the assembly from its operative position back into its transporting position, as illustrated in Figure 1.

It thus will be seen that the objects of this invention have been fully and effectively accomplished. It will be realized, however, that the foregoing specific embodiment has been shown and described only for the purpose of illustrating the principles of this invention and is subject to extensive change without departure from such principles. Therefore, this invention includes all modifications encompassed within the spirit and scope of the following claims.

I claim:

1. A forcefully extensible and contractible support comprising: inner, intermediate, and outer telescoping sections; a member mounted within said outer section for longitudinal movement therein substantially throughout its length; means for forcefully moving said member longitudinally within said outer section; means for selectively connecting said inner section with said member for longitudinal movement therewith between fully extended and fully retracted positions with respect to said intermediate section in response to the movement of said member; means cooperating with said inner and intermediate sections for retaining said inner section in

either of said positions with respect to said intermediate section; means for selectively connecting said intermediate section with said member for longitudinal movement therewith between fully extended and retracted positions with respect to said outer section in response to the movement of said member; and means cooperating with said intermediate and outer sections for retaining said intermediate section in either of said positions with respect to said outer section.

2. A support as defined in claim 1 wherein means for selectively connecting said inner section with said member comprises a power-actuated pin mounted on said inner section for horizontal reciprocation and wherein said member includes an aperture for receiving said pin.

3. A support as defined in claim 2 wherein said means for retaining said inner section with respect to said intermediate section comprises a second power-actuated pin mounted on said inner section for horizontal reciprocation in line with said first-mentioned pin and wherein said intermediate section includes apertures for receiving said second pin.

4. A forcefully extensible and contractible support comprising: inner, intermediate, and outer telescoping section; a piston rod secured within said outer section and having a piston on one end thereof, a cylinder slidably receiving said piston and movable longitudinally in either direction relative to said outer section, first releasable means carried by said inner section and engageable with said cylinder for effecting longitudinal movement of said inner section in either direction with respect to said intermediate section between fully extended and fully retracted positions with respect thereto in response to the movement of said cylinder; first holding means releasably engageable between said inner and intermediate section in either of said positions for restraining relative longitudinal movement therebetween in either direction upon release of said first releasable means; second releasable means carried by said intermediate section and engageable with said cylinder for effecting longitudinal movement of said intermediate section in either direction with respect to said outer section between fully extended and fully retracted positions with respect thereto in response to the movement of said cylinder; and second holding means releasably engageable between said intermediate and outer section in either of said positions for restraining relative longitudinal move-

ment therebetween in either direction upon release of said second releasable means.

5. In apparatus of the type described, the combination comprising: a platform; a telescopic supporting leg including an outer section, at least one intermediate section and an inner section; guide means on said platform mounting said outer section for substantially vertical movement in either direction relative to said platform; a pair of vertically spaced and relatively vertically movable holding means carried by said platform and releasably engageable with said outer section for restraining relative vertical movement in either direction between said outer section and said platform; and power-actuated means operable upon release of one of said pair of holding means to effect relative vertical movement between said platform and said outer section in either direction; a member mounted within said outer section for longitudinal movement with respect thereto in either direction; means for selectively connecting said inner section with said member for longitudinal movement therewith between fully extended and fully retracted positions with respect to said intermediate section; means for retaining said inner section in either of said positions with respect to said intermediate section, means for selectively connecting said intermediate section with said member for longitudinal movement therewith between fully extended and fully retracted positions with respect to said outer section; and means for retaining said intermediate section in either of said positions with respect to said outer section.

6. The combination as defined in claim 5 wherein said intermediate section retaining means comprises a horizontally disposed pin movable into and out of engagement with a section.

7. The combination as defined in claim 6 wherein said outer section includes upper and lower apertures for receiving a pin.
